UNITED STATES PATENT OFFICE.

JOHN S. SHANKS, OF CANTON, OHIO.

HEATING APPARATUS.

1,377,030.

Specification of Letters Patent.

Patented May 3, 1921.

Application filed July 27, 1916. Serial No. 111,700.

To all whom it may concern:

Be it known that I, JOHN S. SHANKS, a citizen of the United States, residing at Canton, in the county of Stark and State of Ohio, have invented certain new and useful Improvements in Heating Apparatus, of which the following is a specification, reference being had therein to the accompanying drawing.

10 My invention relates to improvements in heating apparatus, the primary object of which is to devise such an apparatus employing natural or artificial gas as a fuel which will create a maximum amount of heat with a minimum quantity of fuel. The invention particularly resides in the construction and arrangement of the heating and ventilating elements whereby the above-noted object is accomplished.

20 Another object of the present improvement is to so construct and arrange the heating and ventilating elements whereby the flame from the burner, or burners employed, will be drawn out and extended a great distance beyond the burner, so that its heating capacity will be greatly increased.

A still further object of the present improvement is to devise such a heating and 30 ventilating apparatus which may be used with slight modifications as a clothes drier; hot air furnace; garage heater; enameling oven; steam and hot water boiler and heater, or oven for drying cores, etc., for foundry purposes.

35 A still further object of the present improvement is to devise a burner and radiator tube connected therewith whereby the flame from the burner is drawn a great distance through the radiator tubes, thereby increasing the heating capacity of the burner.

40 Other objects and advantages of the present improvements will be set forth in the following description and drawings, in which—

Figure 1 is a fragmentary view of a heating cabinet or inclosure showing my improved burner, radiator tube and ventilating plates shown in operative position.

50 Fig. 2 is a fragmentary vertical sectional view through the front end of the radiator tube and also through the valve for the burner, showing in detail the construction of the said valve.

55 Fig. 3 is an end view of the burner valve

showing the position of the auxiliary air inlet openings.

Fig. 4 is a dis-assembled fragmentary perspective view of the front end of one of the radiator tubes showing the position and construction of the burner shield and auxiliary air-duct.

Fig. 5 is an enlarged fragmentary perspective view of a modified form of air-duct and air-inlet arrangement for a radiator tube.

Fig. 6 is a diagrammatic view showing one arrangement of the ventilating plates applied to the bottom of a heating cabinet or inclosure.

Fig. 7 is a diagrammatic view of a modified form and arrangement of the ventilating plates positioned in relation to the air-inlet openings.

Fig. 8 is another diagrammatic view showing a modified form and arrangement of the ventilating plates shown in connection with the air-inlet openings for the cabinet or inclosure.

Fig. 9 is a fragmentary perspective view showing radiator tubes arranged and constructed to employ two or more gas burners for heating them, and also showing the arrangement of the radiator tubes and air-inlet pipes when the radiator tubes are applied to the side of a heating cabinet or inclosure.

Fig. 10 is a fragmentary view of a portion of one of the ventilating plates showing the manner of attaching it to a heating cabinet or inclosure.

Fig. 11 is a perspective view, partly broken away, of a heater adapted to be used as a gas heating stove and well adapted for use as a garage heater.

Fig. 12 is a fragmentary perspective view of a radiator tube showing the sections thereof arranged to lie adjacent the bottom and sides of a heating cabinet or inclosure.

Fig. 13 is a perspective view of a heater constructed in accordance with my invention and adapted to be used as a steam or hot water boiler.

All the apparatus shown in the drawings are adapted and constructed to be used in a heating device employing an improved form of gas valve, burner, radiator tubes and ventilating apparatus so constructed that the flame of the burner is drawn out a great distance through the radiator tube for

heating it. The drawings show the arrangement of the radiator tubes, burners and ventilating apparatus as especially adapted for use either in a clothes drier, as is shown in Fig. 1, or as a garage heater, as is shown in Fig. 11; but it is to be understood that a cabinet or inclosure as shown in Figs. 1, 11 and 13 may with or without minor modifications be used in different kinds of heaters 10 within the scope of the appended claims.

Referring now to the drawings in which like reference numerals designate similar parts, referring first particularly to Fig. 1, 1 represents a cabinet or inclosure to be heated. The inclosure may be constructed of any suitable material and may be made of any size or shape, which will be better adapted to accomplish the purpose for which it may be employed. In this figure the heating device, which will be hereinafter described, is shown as applied to the bottom of the cabinet, which arrangement would be especially adapted to and preferably in a clothes drier. The heating device for 20 the cabinet or inclosure 1 comprises a tortuous radiator tube 2, which, as shown is made up of a plurality of sections, in this case consisting of four such sections, numbered on the drawings 3, 4, 5 and 6. The 25 tube, however, may be made of any desired length or have any number of twists and turns, as may be desired, to accomplish its purpose within the inclosure to be heated. In the apparatus here illustrated, the open 30 end of the section 3 of the radiator tube 2 is attached to one of the walls of the cabinet or inclosure 1, the remaining sections of the tube resting upon the ventilating plates 7, 8 and 9, which will be hereinafter described. If the ventilating plates 7, 8 and 9, are not employed, however, the sections of the radiator tube may either rest upon the bottom of the cabinet 1, or be supported therefrom upon suitable brackets, or may 40 be supported at the outlet end of the section 6, which end may of course be attached to the flue or chimney (not shown) since any well-known form of flue or chimney having a damper therein may be employed. A door 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940

radiator tube. The shield has no back or bottom wall. Resting upon the top wall 13 of the shield and lying adjacent the side walls 13 thereof, there is placed an elongated inverted U-shaped member 17, which is of a size to fit over the end of the shield, and, consequently, of a smaller size than the interior of the radiator tube 2, as shown in Figs. 1, 2 and 4. The U-shaped member 17 extends approximately 75 the full length of the radiator tube 2, whereby two passages are formed, one around the outside of the member 17 and one through the member 17. It is, of course, to be understood that the bottom of the radiator tube 80 2, forms the bottom of the passage through the member 17, which member rests upon the bottom of the radiator tube 2. Arranged in front of the shield 12, and inside of the door-frame 11, is a burner formed of an open end pipe 19, which will be hereinafter described in detail. This burner is supplied with gas through a pipe 33, controlled by a gas-cock 20. The burner is provided with a mixing valve 18' for supplying air in the proportion required for combustion, and this air supply may be augmented by opening the door 10 when it is so desired. A further draft for the burner is provided, which will assist in causing a powerful draft 90 through the radiator tube so that the flame acts really like a blast furnace. This air supply consists of a pipe 21, which is arranged beneath the ventilating plates 7 and 9 and above the plate 8, in a manner hereinafter to be described, and has perforations 22 throughout its length, which convey air from the inside of the heating cabinet or inclosure through the pipe 21 and into the passage within the member 17, through an opening 23 in the bottom of the section of radiator tube 3. All of the air which causes the blast for the burner may be drawn through this pipe 21 when so desired, and in this case the door 10 is closed. Of course it 100 is to be understood that the draft is also regulated by the usual form of damper located within the chimney to which the section of tubing 6 is attached, or where a chimney is not employed, a damper 6' may 105 be located in the end of the member 6, which will assist the draft should the tortuous passage made by the radiator tube be of a very great length.

Attention is called to the fact that the 120 opening 23 is beneath the slanting wall 14, of the hood 12, so that the blast of air drawn in through the pipe 21 will not come in direct contact with the burner, which, were a shield not employed would tend to 125 retard the force of the flame to the burner or might in some cases extinguish it. The ventilating plates 7, 8 and 9 are arranged two in a direct line spaced above the bottom of the cabinet 1 and held in their place 130

by means of brackets 24, secured at one end 25 to a lip 26 turned down integral with the ventilating plate. The other end 27 of the bracket 24 is secured to the side of 5 the heating cabinet or inclosure 1. As is shown, the ventilating plates 7 and 9 are in a direct line and spaced apart, and between and below them is situated the ventilating plate 8 held in a manner similar 10 to the plates 7 and 9. The pipe 21, which is the main inlet pipe for the burner 18 and passes through the ventilating plate 7 and beneath the plates 7, 8 and 9.

The apparatus operates as follows:

15 After the burner 19 has been lighted and the articles, clothes, cores or any other articles which it may be desired to dry out have been placed within the cabinet 1, the cold and moist air within the inclosure is 20 drawn into the pipe 21 up against the burner 19 where it comes in contact with the flame of the burner. The current of air is deflected by means of the inclined wall 14 of the hood 12, and directed through the tortuous 25 passages of the radiator tube, the draft being, of course, controlled by the tortuous passage and also by the damper 6 which is located in the end thereof. The flame of the burner 19 also causes a draft 30 of air outside of the member 17, which will heat the outside of the radiator tube 2. A very strong current of air may be caused between the outside of the member 17 and the inside of the radiator tube 2, when the 35 door 10 is opened. Through this arrangement it is seen that the moist air in the cabinet is drawn into the pipe 21 and brought in direct contact with the burner and thereby becomes thoroughly heated. 40 This heated air is preferably discharged at the end of the radiator tube 2 into the cabinet again. Where the radiator tube 2 is found to provide sufficient heat for the inclosure the heated air within the said radiator tube is discharged outside of the cabinet. 45 In this case the end of the tube 2 is connected with any form of flue or discharges outside of the cabinet as is shown in Fig. 12. The air within the cabinet is also 50 heated by coming in contact with the outside of the radiator tube 2, which has become heated in a manner heretofore described. By locating the draft pipe 21 beneath the 55 ventilating plates 7, 8, and 9, in the manner shown and described, the cool air which descends after the device has been started will become pocketed beneath the ventilating plates 7, 8 and 9 and, consequently, will be drawn in by the pipe 21. This air being 60 relatively cooler than the air above the plates 7, 8 and 9, which is always in contact with the radiator tube 2, will cause a greater draft through the pipe 21. This strong draft of cold air will in its passage through 65 the radiator tube draw the flame an almost

incredible distance out through the radiator tube. This drawing out of the flame both causes very hot air to be discharged at the exhaust end of the radiator tube and also assists in heating the member 17, which 70 will of course transmit some of its heat to the outside of the radiator tube and assist in heating the outside of the said tube. From the foregoing it is apparent that there are two currents of air passing through the radiator tube, one from the outside of the heating cabinet 1, through the door 10 and through the radiator tube outside the member 17, and the other current being drawn 75 into the pipe 21 and inside of the member 80 17. In this manner the moist air within the cabinet is thoroughly heated and fresh air is also drawn in, which is of course more potent in its drying qualities than the air within the cabinet which of course becomes 85 dead as it is used over and over. Whether a flue is attached to the end of the radiator tube or not, an outlet opening is, of course, provided in the cabinet 1 at any point, but it is preferably located at a point near the 90 top of the cabinet. In many cases where the inclosure is small the use of the member 17 forming the auxiliary air passage will be found unnecessary. In all cases where the radiator tube 2 is also found sufficient the member 17 is dispensed with. 95

From the foregoing description, it has been pointed out that the open end pipe 18 for burner 19 is provided with a valve 18^a for supplying its air for combustion whether 100 the door 10 is open or closed. This valve consists of a hollow body portion 28, which terminates in an internally screw threaded passage 29 into which is screwed the end 30 of the burner pipe which extends upwardly 105 and in through the door casing 11, and is provided with the open end 18^a. This burner is arranged in front of the shield 14. Of course it is to be understood that the burner pipe 19 may be made in a straight 110 line with the mixing valve in which case the turn in the said pipe is made below the mixing valve. This construction will provide an absolutely uninterrupted passage of combustible fuel to the burner. The other end 115 of the casing 28 is provided with a longitudinally extending portion 31 having a passage 32 therethrough and into the outer end of which is fitted the end of the gas inlet pipe 33. The member 28 is of conical 120 form, its greatest diameter being located above the portion 31. The end of this conical portion is provided with a plurality of openings 34. Slidably mounted on the outside of the portion 31 is a member consisting of a sleeve 35 and an annular disk 36, which has a concave face 37 adapted to fit against the end of the conical portion of the member 28 which is made convex, as is shown at 38. The annular disk 36 is adapt- 125 130

ed to be moved in and out on the member 31 and varies the distance between the face of the disk 36 and the face of the conical portion of the member 28, whereby a varied opening is caused between these two members which will lessen or enlarge the passage through which air may pass from the outside in through the openings 34. A set-screw 39 is provided for the purpose of locking the slidable sleeve 35 in any desired position. It is oftentimes found difficult to adjust to a fine degree, the exact amount of air for perfect combustion fed in through the openings 34 and for this reason an auxiliary adjustment is provided. This adjustment consists in providing a plurality of openings 40 through the disk 36, which openings are in a line to register with the openings 34 in the conical portion of the member 28. Another member consisting of a sleeve 41 and an annular disk 42 is mounted on the outside of the sleeve 35 and this disk is provided with a plurality of openings 43, which are adapted to be thrown in and out of communication with the openings 40 in the annular disk 36 by turning the disk 42. A lock-nut 44 is mounted on external-screw threads 45 on the outside of the sleeve 35 for the purpose of locking the disk 42 in any position in which it is turned. After the air supply for the burner, whether the burner uses artificial or natural gas, is adjusted to an approximate degree for perfect combustion, the disk 42 may be rotated to feed a little more air by throwing into full register or partial register the openings 40 and 43, which will admit additional air into the openings 34, and thence to the burner, as will be readily understood. From the foregoing, it is apparent that the valve is provided with two air-inlets, one through the openings 34, which are controlled by means of moving the disk 36 toward and away from the end of the conical portion of the valve 28, and the other the partial opening or closing of the ports 43 and 40 for supplying air through the openings 34. A burner constructed in this manner and coupled with the ventilating elements as described creates a blast heating flame, which flame can be reduced in volume or intensity or made shorter by cutting down the volume of gas and the volume of air carried through the valve. The adjustments on the valve together with the adjustment of the damper in the outlet pipe permits the accurate regulation of the flame and consequently the heat thrown out by the radiating tube.

Reference will now be had to Fig. 5, which shows a modified form of ventilating plate used in connection with the radiator tube. In this form the ventilating plate comprises a U-shaped member 46 of a size 65 to fit around the radiator tube 2 and leave

a small space therebetween. The member 46 may be constructed of a shape and length equal to the length of the radiator tube or may be made shorter if desired. In this construction a fresh air pipe 47 is employed 70 which draws air from outside of the cabinet or inclosure and discharges it around the radiator tube 2. This is accomplished by carrying the pipe 47 in through an opening 48 in one side of the member 46 and 75 then extending the pipe longitudinally and below the radiator tube 2, as shown at 49. The section 49 of the pipe 47 is provided with a plurality of perforations 50 to spread the discharge of air. The pipe 47 may also 80 enter through the front of the member 46, as is shown in dotted lines at 51, but in each case the portion 49 of the pipe 47 is arranged at one side of the center of the radiator tube so as not to interfere with the 85 air intake opening 23 for the burner 19.

Another modified form and arrangement of ventilating plates are shown diagrammatically in Figs. 6, 7, and 8. Fig. 6 shows three plates 52, 53 and 54, arranged similarly to the plates 7, 8 and 9, as employed in Fig. 2. Fig. 7 shows the use of the three plates 52, 53 and 54, but in addition fresh air openings 55 are provided arranged in a line above the plate 52 for admitting fresh air from outside the cabinet or inclosure. In this case the fresh air pipe 47, shown in Fig. 5, is dispensed with. Sometimes in practice it may not be found necessary to employ three plates, but only 90 the two plates 52 and 53 arranged as shown in Fig. 8 also employing the fresh air openings 55. It is to be understood in this connection that the U-shaped plate 46 surrounding the radiator tube may be used in addition to the plates 52, 53 and 54, according to the need of greater or less circulation and 95 radiation of air within the cabinet. 100

Very often when the inclosures to be heated are very large it is necessary to employ two or more burners instead of one and a greater length of radiator tube. In this case the structure shown in Fig. 9 is employed. This construction embodies the same radiator tube 2, shield 14 and burner 110 110 (not shown) as is employed in the construction shown in Fig. 1. In this case, however, a second section or radiator tube 56 is employed, having one end attached directly below the opening 23 in the radiator tube 2 which in this case is enlarged. The other end of the radiator tube 56, which is also arranged tortuous, is provided with a shield 14, burner (not shown) and air inlet 23. To this air inlet 120 125 23 the usual form of air inlet pipe 21 is connected. When a plurality of burners are employed, as here shown, a plurality of fresh air pipes 58 are provided arranged in close proximity to the pipe 21. The 130

radiator pipe 56 is shown as arranged for fitting adjacent a side of the inclosure and the radiator 2 may be shaped similar to the tube 56, or may run at right angles, 5 (similar to Fig. 1) across the top of the inclosure. It is to be understood that any number of burners may be built up depending upon the amount of heat required. Also the fresh air for the entire number of 10 burners is drawn in through the bottom air opening 23. The air inlet 23 shown above the pipe 57 is made larger than the air inlet 23 in the bottom of the first burner box, the air openings in the second, third and 15 fourth, and any number of succeeding burner boxes would be varied depending upon the radiation desired and the distance it is desired to draw the flame out. When a plurality of burners are used additional 20 fresh air may be drawn in through the door 10 when the door is opened or through permanent openings made around the door.

When it is desired to situate the radiator tubes along the top or bottom and one side 25 of the inclosure, they are arranged in the manner shown in Fig. 12. In this case the burner is situated at the point 59, the other end 60 of the tube being connected with a usual form of flue or chimney when this is 30 desirable or the heated air is discharged directly into the cabinet or inclosure.

As has been stated heretofore, a device 35 employing the general principles of ventilation and the burner and radiator tubes shown herein may with slight modifications be used as a garage heater, hot water or steam heater and boiler, hot air furnace, or drier for foundry purposes. The device shown in Fig. 1 is particularly adapted for 40 use as a clothes drier, (the bottom of the cabinet not being used).

Reference will now be had to Fig. 11, 45 which shows my invention embodied in a gas heating stove which is also well adapted for use as a garage heater, which structure, however, can be used also as a hot water or steam heater and boiler, as will be hereinafter described. This structure comprises a cabinet or inclosure 60', here shown 50 of rectangular shape, mounted upon suitable legs 61, which are preferably made of considerable length so as to place the heater itself and burner thereof well above the floor and away from any oil, gasoline, or 55 vapors which might be in the garage. The cabinet 60' is provided with a vertical partition 62, forming a small compartment 63, near one end thereof and a large compartment 63'. In the compartment 63 and ad- 60 jacent the bottom thereof, one end of a radiator tube 64 is situated having the same form of burner, shield, gas inlet, etc., shown in Figs. 1, 2, 3, and 4. The radiator tube 64 is provided with a plurality of tortuous sec- 65 tions 65 winding within the cabinet, the

final section terminating in a portion 66 extending through an opening 67 in the top of the inclosure and provided with a suitable damper 68. The portion 66 in this case may also be made to end below the perforations 70 and discharge within the inclosure or cabinet as is shown and explained in reference to Fig. 1. The top and bottom of the large compartment 63' is provided with perforations 69 and 70 respectively, the purposes of 75 which will be hereinafter set forth. The top of the small compartment 63 is also provided with perforations 71 and a horizontally mounted ventilating plate 72, arranged near its bottom, but spaced a short 80 distance thereabove. This plate 72 is provided with perforations 73 arranged at each end thereof. The vent pipe 21 for the burner (not shown) lies directly beneath and against the ventilating plate 72. Be- 85 sides the usual door 10 at the front end of the radiator tube, another door 74 is provided in the front of the inclosure 60, to provide means for lighting the burner and also as a fresh air inlet when it is so desired. 90

The apparatus here described operates as follows: The burner (not shown) is first lighted after opening the doors 74 and 10 and the said doors are then closed. The proper amount of air for combustion is sup- 95 plied to the burner through the mixing valve heretofore described, the compartment 63 getting its air from outside the cabinet through the perforations 71, in the top thereof. These are the only air inlets 100 for supplying air to the burner and they are arranged in the top of the heater so that even were the heater set upon the floor without the use of the legs 61, the air drawn into the burner would come from a point well 105 above the floor and away from any oil or gaseous fumes that might be there. The pipe 21 for causing the blast in the burner receives its air through the perforations 71 in the top of the compartment 63 and down 110 through the perforations 73 in the ventilating plate 72. When a greater blast is desired the door 10 may be opened and in some cases the door 74 may also be opened when a very powerful draft is desired. The 115 air in the garage is heated by passing into the compartment 63', through the perforations 69, around the radiator 65 and out through the perforations 70 in the top of the compartment 63'. Hot air is also dis- 120 charged through the end 66 of the radiator tube which, due to its long passage through the tortuous tube and the system of heating and ventilating embodied, will be freed of 125 all gaseous fumes and odors. This construction of heater may with slight changes be used as a hot water or steam boiler and heater as is shown in Fig. 13. In this case the partition 62 is not employed, and one continuous run of radiator tube 2 is pro- 130

vided which will heat the water passing through the heater compartment which in this case is the combined compartments 63 and 63'. The open end of the section of radiator tube 65 is securely fastened or welded to the outer casing or jacket 1, so that no water can work out around the edge where it is connected. The partition plates 73 and door 74 are dispensed with and the 10 burner end 66 of the radiator tube 65 is connected to the casing in the manner shown in Fig. 1. Where the air inlet pipe 21 and the burner end 66 of the radiator tube extends without the cabinet they are welded to the 15 casing so as to be air and watertight. In this case the perforations are not employed and water is admitted into the compartment by tapping and threading a pipe *a* for admitting water. An outlet pipe *b* is 20 made in a similar manner and the inclosure may then be filled with water to be heated. The water is heated by coming in contact with the heated radiator 2, through which the gas flame, heat and products of combustion 25 are carried in the manner heretofore described.

The general construction of Fig. 1, may be utilized in a hot air furnace, and in this case the radiator tube may be longer and 30 have a greater number of bends, and a plurality of burners and burner boxes may be employed in a manner similar to that shown in Fig. 9.

Attention is called to the fact that when 35 the structure shown in Fig. 1 is constructed to be used only as a clothes drier, the air is changed constantly. The fresh air is drawn in the cabinet through openings, and after rising to top of cabinet, the down 40 draft brings the same heated air back to the bottom or lower part of the cabinet, being drawn in pipe 21 through openings 22, being conducted or drawn into radiator pipe 2 and through the opening 23 as shown in 45 Fig. 9. The air when charged with moisture is converted into heated air as it comes in contact with and is drawn through gas flame. The air is drawn through the radiator 2, into the chimney opening. In this 50 way fresh air is drawn in cabinet or inclosure and the air withdrawn is in accordance with the strength of chimney draft.

Having thus described my invention what I claim and desire to secure by Letters Patent is:—

1. An improved heating apparatus comprising a housing, a serpentine-shaped radiator tube within the housing, the tube having inlet and outlet ends opening outside of 60 the housing, a burner in the inlet end of the tube, a perforated shield in the inlet end of the tube and in front of the burner, the tube having an air inlet opening in rear 65 of the shield and communicating inside of

2. An improved heating apparatus comprising a housing, a horizontally extending radiator tube at the bottom of the housing, ventilating plates below the tube, and a burner in the inlet end of the tube. 70

3. An improved heating apparatus, comprising an inclosure, a plurality of ventilating plates arranged adjacent one wall thereof, a radiator tube within the inclosure, a burner in one end of the radiator tube, and 75 a pipe arranged below the ventilating plates and supplying air in front of the burner for the purpose described.

4. An improved heating apparatus comprising an inclosure, a radiator tube therein, a plurality of ventilating plates arranged below the said tube, a burner in one end of the tube, and a pipe beneath the 80 ventilating plates and supplying air to a point within the radiator tube and in front of the burner. 85

5. An improved heating apparatus comprising an imperforate radiator tube, a burner in one end of the said tube, a perforated shield extending transverse the tube 90 and in front of the burner, and an air supply for the tube.

6. An improved heating apparatus comprising a housing, a radiator tube therein consisting of an outer tube and an inner 95 tube inclosed within the outer tube, the inlet end of the inner tube embraced within the outer tube, a perforated shield across the inlet end of the inner tube, and a burner within the outer tube and in front of the 100 perforated shield.

7. An improved heating apparatus, comprising a radiator tube having two passages, one passage within the other, a shield closing the front end of one of the passages, a 105 burner in the front end of the radiator tube, and in front of the said shield, and means for supplying air on the opposite side of the shield from the burner.

8. An improved heating apparatus comprising a radiator tube, a deflecting shield in one end thereof, the said shield comprising a body portion having an inclined front wall, side walls, top walls and an open back and bottom, the said radiator tube having 115 an air inlet opening under the said shield, and a burner within the radiator tube and in front of the inclined wall of the shield.

9. An improved heating apparatus comprising a radiator tube, a deflecting shield 120 in one end thereof, the said shield comprising a body portion having an inclined front wall having perforations therein, side walls, top wall and an open back and bottom, the said radiator tube having an air inlet opening under the said shield, and a burner within the radiator tube and in front of the inclined wall of the shield. 125

10. An improved heating apparatus, comprising a radiator tube, a deflecting shield 130

in one end thereof, the said shield comprising a body portion having an inclined front wall, side walls, top wall and an open back and bottom, an inverted U-shaped trough member within the tube and having its top resting on the top wall of the shield, the said radiator tube having an air inlet opening under the said shield and a burner within the radiator tube and in front of the inclined wall of the shield.

11. An improved heating apparatus comprising an inclosure, a radiator tube therein, a burner within the said tube, a plurality of ventilating plates arranged adjacent the heating mechanism, the inclosure having air inlet openings arranged in a line with the top surface of one of the ventilating plates.

12. An improved heating apparatus comprising an inclosure, a radiator tube therein, a burner within the tube, a plurality of ventilating plates arranged adjacent the radiator tube, the said plates spaced apart but having their edges overlapping, air inlet openings arranged in a line with the top surface of one of the ventilating plates for supplying fresh air to the radiator tube, and the inclosure having an outlet.

13. An improved heating apparatus com-

prising a housing, a radiator tube within the housing having an outlet opening outside the housing, a burner in the inlet end of the tube having a valved opening for drawing air from outside the housing, and an opening in the inlet end of the tube for drawing moisture laden air into the radiator from inside the housing.

14. An improved heating apparatus comprising a housing, a radiator tube within the housing having an outlet opening outside the housing, a burner in the inlet end of the tube, having a valved opening for drawing air outside the housing, and an opening in the inlet end of the tube for drawing moisture laden air into the radiator from inside the housing, and an inlet opening in the housing remote from the moist air opening in the inlet end of the tube for drawing fresh air into the housing, thereby creating a circulation of air within the housing.

In testimony whereof I hereunto affix my signature in the presence of two witnesses.

JOHN S. SHANKS.
